REVERSING APPARATUS FOR FURNACES

Otto Reiner, Rheinhausen-Nrh.-Hochemmerich,
Germany; vested in the Attorney General of
the United States

Application March 9, 1940, Serial No. 323,160
In Germany November 15, 1937

2 Claims. (Cl. 158—7.5)

1

This invention relates to apparatus for reversing the heating gas current, the air current and the waste-gas current, also for supplying the air in connection with industrial furnace plants operating with alternating gas and air currents.

It is known to shut-off the heating gas current prior to the reversal of the furnace by means of valves in order to prevent chimney losses during the reversal. This manner of operating causes an increase of the pressure in the gas conduit so that other furnaces connected to the same gas conduit receive too large amounts of the gas, of which a part escapes in an unburnt state through the chimney because of the lack of air. Besides, any combustion of gas in the furnace ceases when the heating gas current is shut-off, in consequence whereof no smoke gases for producing a draught in the chimney are generated, whereby the furnace is sucked empty during this period and cold air finds access into the furnace and the heating chambers. The consumption of heat units for compensating such a drop of temperature is larger than the consumption due to the loss of heating gas, in consequence whereof the losses of chimney gas cannot be wholly prevented by a prior shutting-off of the heating gas current.

It is furthermore known to reverse, while the furnace is being reversed, first the heating gas current and thereafter the air current in order to attain separate sucking-off of the current of the return gas and the current of the return air through the chimney so that no explosions in the chimney flue can occur. This procedure suffers, however, from the drawback that the combustion of the gas in the furnace side having been heated does not uniformly cease and that after the reversal of the furnace the gas and the air do not uniformly escape whereby a substantial increase of the fusing time and an increased gas consumption is entailed.

An object of the present invention is to obviate the above-mentioned disadvantages of the former reversing methods and devices by apparatus in which the gas supplied to the furnace is continually deflected without any loss of gas by the chimney conduit and without any throttling or shutting-off. A characteristic feature of the invention is that while carrying out the reversing procedure first the abstraction of the waste-gases from the gas chamber of that furnace side which up to then had been in connection with the discharge chimney through said chamber, as well as through the appertaining air chamber, is interrupted and thereafter the waste-gases from said furnace side are sucked away solely through the air chamber until the reversing has been finished. This sucking takes place in an increased degree relatively to the preceding sucking and thereafter, the supply of air also

2

to the furnace side having been heated is interrupted so that the air supply to both furnace sides is shut-off in the common air conduit. Simultaneously therewith the reversal of the supply of the heating gas to, and the withdrawal of the waste-gas from, the two furnace sides, as well as the supply of air to the furnace side now to be heated, are effected with such a small delay relatively to the supply of the heating gas to this furnace side that the current of air and the current of waste-gas meet one another at the burning place of this furnace side which is now to be heated so that at the moment in which the reversal has been finished the correct heating of the furnace side in question takes place at once.

Thus the supply of gas to the furnace takes place uninterruptedly so that after the reversal of the gas current the smoke gases present in the regenerative chambers of the furnace side having been heated up to then are pressed into the furnace during the interruption and can be sucked away through the chimney, so that at the instant at which the heating gases enter into the furnace the supply of the air into the furnace takes place.

Another advantage provided by the present invention is that owing to the continuous supply of the gas smoke gases effecting the sucking action in the chimney are likewise continuously available for this purpose so that the chimney is never able to suck cold air (false air) into the furnace and into the heating chambers, whereby equally high temperatures in the furnace are attained.

Still another advantage presented by the invention is that the supply of the gas and of the air to the furnace side having been heated up to then ceases proportionally and the escape of the gas and the air after the furnace reversal at the burner take place simultaneously so that neither an oxidising, nor a reducing combustion of the heating gases occurs, nor is an excess of gas or of air supplied to the furnace.

Finally, also the advantage exists that the return air current coming from the air generator chambers is sucked off through the chimney separately from the return gas current coming from the gas generator chambers, the gas and the air being simultaneously reversed, whereby any possibility of the occurrence of an explosion is completely prevented.

The invention will be more thoroughly understood upon reference to the annexed drawings and the following description wherein an exemplary embodiment of the invention is disclosed.

In the drawings—

Figure 1 is a top plan view showing apparatus according to the invention.

Figures 2, 3 and 4 are fragmentary vertical sectional elevational views taken substantially on

the planes indicated by the lines II—II, III—III, and IV—IV, respectively, in Figure 1.

In this constructional form of the device the shutting-off members are formed by disk valves combined with a water seal, but I wish it to be understood that instead of disk valves also valves of another design, as well as other suitable shutting-off members, may be used without affecting the scope of the invention.

In the drawings the right-hand side of the furnace plant with its reversing device, or reversing members respectively, includes the gas chamber Gr and the air chamber Lr , connected to the conduit K which is connected to the chimney, whereas the gas chamber Gg of the left-hand furnace side is supplied with heating gas and the air chamber Lg of said side with compressed air.

10 (Fig. 3) denotes the common gas supply conduit below which is arranged a change-over flap 4 located between the branch pipes $3g$ and $3r$ which terminate at the heating gas reversing valves $2g$ and $2r$, the said flap 4 shutting-off in the position shown in Fig. 3 the communication between the conduit 1 and the pipe $3r$. The valve $2r$ is closed, whereas the valve $2g$ is open. In the conduit 10 leading from the gas chamber Gr to the chimney is arranged a disk valve $5r$ and in the conduit 11 leading from the gas chamber Gg to the chimney is arranged a valve $5g$. In the position of these valves as shown the valve $5r$ is open and the valve $5g$ closed. In the common air supply pipe 6 which leads to the air chambers Lr and Lg is arranged a throttle flap 7 at the place shown in Figs. 1 and 4. When this flap is turned from the position shown in Figs. 1 and 4, in which it is open, into the other position it closes and interrupts the supply of air to the air chambers of both sides of the furnace.

15 In the pipe 14 leading from the common air supply pipe 6 to the air chamber Lr is arranged a valve $8r$, and in the pipe 15 leading from the pipe 6 to the air chamber Lg is arranged a valve $8g$. Furthermore, a valve $9r$ is arranged in the pipe 20 connecting the air chamber Lr with the chimney, and a valve $9g$ is arranged in the pipe 21 connecting the air chamber Lg with the chimney. In the position of the several members mentioned the valve $8r$ is closed and the valve $8g$ open, whereas the valve $9r$ is open and the valve $9g$ closed. There is, therefore, in these positions of these valves the left-hand side of the furnace heated, whereas the right-hand side of the same communicates with the chimney through the gas chamber Gr , as well as through the air chamber Lr .

20 If now the supply of gas and of air to the furnace be reversed, first an electromotor (not shown) is started in known manner and rotated with such a low speed that the valve $5r$ is slowly lowered and at the same time the valve $2r$ is opened. The valves $5r$ and $2r$ are connected with one another by a rope, and as the valve $5r$ is heavier than the valve $2r$ the valve $5r$ will lift the valve $2r$ when it is lowered. Owing to the slow movement of the valve $5r$ the communication between the gas chamber Gr and the chimney will be slowly interrupted and when the valve $5r$ has been completely closed the waste gases will be sucked off from the right-hand side of the furnace through the air chamber Lr , this sucking off of the gases from the right-hand side of the furnace through the air chamber Lr taking place more strongly than the gases had been sucked off prior thereto through the air chamber Lr .

25 After the valves $2r$ and $5r$ have been reversed,

the change-over flap 4 is suddenly turned over by means of a motor provided for the purpose, and simultaneously therewith also the throttle flap 7 in the air pipe is suddenly turned over by an electro-motor or any other known electro-magnetic implement into its closing position so that from this moment the air supply to the air chamber Lg is interrupted so that neither of the two furnace sides receives air. From the moment of the reversal of the shutting-off devices the heating gas is supplied on the right-hand side of the furnace into the gas chamber Gr but, no air is supplied to the air chamber Lg of the left-hand side of the furnace whereby no unburnt air, or false air, enters into the furnace through the air chamber Lg of the left-hand side of the furnace to conduct oxygen to the molten steel, the quality of which would be deteriorated thereby.

30 Besides, by shutting-off the air supply by means of the shutting-off device 7 no cold air is passed into the chimney flue whereby the draught in the chimney would be reduced.

35 After the position of the change-over flap 4 has been reversed and the shutting-off device 7 has been closed, the electromotors pertaining to the valves $8r$ and $8g$ are started whereby the valve $8r$ will be opened and the valve $9r$ will be closed and also the valve $8g$ will be closed and the valve $9g$ opened. Thus, all valves engaged in the air supply are reversed at the same time.

40 When this has been effected the shutting-off device 7 located in the air blast conduit is again opened and either simultaneously therewith or a moment thereafter the position of the valves $2g$ and $5g$ is reversed therewith the reversing procedure will be completed.

45 From the moment of the re-opening of the shutting-off device 7 air flows to the right-hand furnace side into the air chamber Lr , and the reversal of the air supply takes place relatively to the reversal of the gas supply by the opening of the valve $2r$ so that when the heating gas arrives at the burning place of the right-hand furnace side also the air arrives at said place so that now the heating of this side of the furnace commences without solely gas or solely air being pressed into the right-hand side of the furnace. This is rendered possible by the fact that the conduits through which the gas passes to the furnace are longer than the conduits through which the air passes from the reversing device to the furnace, so that, for instance, 25 seconds will elapse between the time at which the flap 4 is turned over and the time gas arrives at the place of burning, whereas only 15 seconds will elapse from the time at which the shutting-off device 7 is again opened, so that 10 seconds are available for the reversal of the air supply.

50 When the above described reversing procedure has been finished, the right-hand side of the furnace is heated, whereas the left-hand side of the same is connected with the chimney through the air chamber Lg and the opened valve $9g$, as well as through the gas chamber Gg and the opened valve $5g$.

55 The provision of a separate shutting-off device 7 for the temporary interruption of the supply of air, instead of effecting this interruption by stopping the fan producing the compressed air, provides improvements in the reversing device, as stopping and starting a fan requires by far too much time.

60 A reversing device suited for carrying out the

invention can be designed without a change-over flap, such as 4, but a thus modified construction would operate less advantageously. With such a modified construction the driving device for the several valves must be so designed that (starting again from the position of the valves as in Fig. 1) first the valve 5r is lowered whereupon first of all waste-gas is sucked away from the right-hand side of the furnace only through the air chamber Lr. Then the gas valves 2r and 2g are reversed which causes the reversal of the gas supplied to the furnace, and simultaneously with the movement of said valves the supply of air is interrupted by the shutting-off device 7, whereafter the further reversing procedure takes place practically in the same manner as above described, the only exception being that, as the valve 2g is being closed while the valve 2r is being opened, only the valve 8g need be opened at the instant the reversal of the air is being finished.

It is also possible to do without the separate valve 7, but the control device must then be so designed that after the gas valve 2r has been opened, first the air valve 8g is closed, and only then the other valves are reversed, so that, with this reversing procedure, the supply of air to the two furnace sides is likewise stopped for a certain period of time. The procedure entails the necessity that the reversal of the valve 8g be done ahead of the reversal of the valves 9r, 9g and 8r.

After a push-button switch (not shown) has been actuated, first the valve 5r is closed, whereby the waste-gas current flowing from the gas chamber Gr to the chimney K is interrupted. The entire amount of the waste-gas is then sucked away through the air chamber Lr. Now the following valves are moved simultaneously, the valve 2r is opened and the valves 2g and 8g are closed, whereby the gas current is continually deflected from the left-hand side of the furnace to the right-hand side thereof. As the valves 2g and 8g have been closed at the same time, the combustion of the gas in the left-hand side of the furnace ceases proportionally, whereby neither an oxidising combustion, nor a reducing combustion of the heating gas can arise. The supply of air to the furnace is interrupted in that the valve 8g is closed. Now the valves 9r and 9g are likewise moved at the same time and with equal transverse sections, the valve 9r being closed and the valve 9g opened, whereby the waste-gas current is deflected from the air chamber Lr to the air chamber Lg. The entire amount of the waste-gas is then sucked away by the chimney through the air chamber Lg and simultaneously therewith the air in the air chamber Lg is sucked away together with the waste-gas flowing to the chimney, whereby no return air comes in contact with the return gas from the gas chamber Gg and, therefore, no ignition in the chimney flue can occur. Thereafter the valve 8r is opened by suitable means provided for the purpose and the current of air is thereby released with a certain delay so that the furnace is fed with gas and with air at the same time. Thereafter the valve 5g is opened whereby the current of gas will be liberated as soon as the return air still present in the air chamber Lg has been completely sucked away by and through the chimney, and simultaneously therewith the return gas still present in the gas chamber Gg will be sucked away. All this having been accomplished, the

furnace is reversed and operates with continual supply of gas and continual withdrawal of waste-gas in known manner.

I claim:

- 5 1. In apparatus for reversing the flow of heating gas and air in an alternately heated regenerative furnace having air chambers and gas chambers; a gas supply conduit having branches, a valve for directing gas from said supply conduit into any of said branches, a chimney conduit connected between each furnace gas chamber and related ones of said branches, other valves for closing off the said branches individually, valves for individually closing the chimney conduits at points between the chimney and the branches of the gas conduit, an air supply conduit, a further valve for closing said air supply conduit, said air supply conduit having branches connected with the furnace air chambers, branches connecting said chimney conduit with the air supply conduit branches, further valves for individually closing the air supply conduit branches, and other valves arranged for individually closing the chimney conduit branches at points between the connections of the chimney conduit branches with the chimney conduit and with said air supply conduit branches.
- 10 2. In apparatus for reversing the flow of heating gas and air in an alternately heated regenerative furnace having two air chambers and two gas chambers; a gas supply conduit having two branches, a valve for directing gas from said supply conduit into either of said branches, a chimney conduit connected between each furnace gas chamber and the related branch, other valves for closing off said branches individually, valves for individually closing the chimney conduits at points between the chimney and the branches of the gas conduit, an air supply conduit, a further valve for closing said air supply conduit, said air supply conduit having two branches connected with the furnace air chambers, two branches connecting said chimney conduit with the air supply conduit branches, further valves for individually closing the air supply conduit branches, and other valves arranged for individually closing the chimney conduit branches at points between the connections of the chimney conduit branches with the chimney conduit and with said air supply conduit branches.
- 15 3. In apparatus for reversing the flow of heating gas and air in an alternately heated regenerative furnace having air chambers and gas chambers; a gas supply conduit having two branches, a valve for directing gas from said supply conduit into either of said branches, a chimney conduit connected between each furnace gas chamber and the related branch, other valves for closing off said branches individually, valves for individually closing the chimney conduits at points between the chimney and the branches of the gas conduit, an air supply conduit, a further valve for closing said air supply conduit, said air supply conduit having two branches connected with the furnace air chambers, two branches connecting said chimney conduit with the air supply conduit branches, further valves for individually closing the air supply conduit branches, and other valves arranged for individually closing the chimney conduit branches at points between the connections of the chimney conduit branches with the chimney conduit and with said air supply conduit branches.
- 20 4. In apparatus for reversing the flow of heating gas and air in an alternately heated regenerative furnace having air chambers and gas chambers; a gas supply conduit having two branches, a valve for directing gas from said supply conduit into either of said branches, a chimney conduit connected between each furnace gas chamber and the related branch, other valves for closing off said branches individually, valves for individually closing the chimney conduits at points between the chimney and the branches of the gas conduit, an air supply conduit, a further valve for closing said air supply conduit, said air supply conduit having two branches connected with the furnace air chambers, two branches connecting said chimney conduit with the air supply conduit branches, further valves for individually closing the air supply conduit branches, and other valves arranged for individually closing the chimney conduit branches at points between the connections of the chimney conduit branches with the chimney conduit and with said air supply conduit branches.
- 25 5. In apparatus for reversing the flow of heating gas and air in an alternately heated regenerative furnace having air chambers and gas chambers; a gas supply conduit having two branches, a valve for directing gas from said supply conduit into either of said branches, a chimney conduit connected between each furnace gas chamber and the related branch, other valves for closing off said branches individually, valves for individually closing the chimney conduits at points between the chimney and the branches of the gas conduit, an air supply conduit, a further valve for closing said air supply conduit, said air supply conduit having two branches connected with the furnace air chambers, two branches connecting said chimney conduit with the air supply conduit branches, further valves for individually closing the air supply conduit branches, and other valves arranged for individually closing the chimney conduit branches at points between the connections of the chimney conduit branches with the chimney conduit and with said air supply conduit branches.
- 30 6. In apparatus for reversing the flow of heating gas and air in an alternately heated regenerative furnace having air chambers and gas chambers; a gas supply conduit having two branches, a valve for directing gas from said supply conduit into either of said branches, a chimney conduit connected between each furnace gas chamber and the related branch, other valves for closing off said branches individually, valves for individually closing the chimney conduits at points between the chimney and the branches of the gas conduit, an air supply conduit, a further valve for closing said air supply conduit, said air supply conduit having two branches connected with the furnace air chambers, two branches connecting said chimney conduit with the air supply conduit branches, further valves for individually closing the air supply conduit branches, and other valves arranged for individually closing the chimney conduit branches at points between the connections of the chimney conduit branches with the chimney conduit and with said air supply conduit branches.
- 35 7. In apparatus for reversing the flow of heating gas and air in an alternately heated regenerative furnace having air chambers and gas chambers; a gas supply conduit having two branches, a valve for directing gas from said supply conduit into either of said branches, a chimney conduit connected between each furnace gas chamber and the related branch, other valves for closing off said branches individually, valves for individually closing the chimney conduits at points between the chimney and the branches of the gas conduit, an air supply conduit, a further valve for closing said air supply conduit, said air supply conduit having two branches connected with the furnace air chambers, two branches connecting said chimney conduit with the air supply conduit branches, further valves for individually closing the air supply conduit branches, and other valves arranged for individually closing the chimney conduit branches at points between the connections of the chimney conduit branches with the chimney conduit and with said air supply conduit branches.
- 40 8. In apparatus for reversing the flow of heating gas and air in an alternately heated regenerative furnace having air chambers and gas chambers; a gas supply conduit having two branches, a valve for directing gas from said supply conduit into either of said branches, a chimney conduit connected between each furnace gas chamber and the related branch, other valves for closing off said branches individually, valves for individually closing the chimney conduits at points between the chimney and the branches of the gas conduit, an air supply conduit, a further valve for closing said air supply conduit, said air supply conduit having two branches connected with the furnace air chambers, two branches connecting said chimney conduit with the air supply conduit branches, further valves for individually closing the air supply conduit branches, and other valves arranged for individually closing the chimney conduit branches at points between the connections of the chimney conduit branches with the chimney conduit and with said air supply conduit branches.
- 45 9. In apparatus for reversing the flow of heating gas and air in an alternately heated regenerative furnace having air chambers and gas chambers; a gas supply conduit having two branches, a valve for directing gas from said supply conduit into either of said branches, a chimney conduit connected between each furnace gas chamber and the related branch, other valves for closing off said branches individually, valves for individually closing the chimney conduits at points between the chimney and the branches of the gas conduit, an air supply conduit, a further valve for closing said air supply conduit, said air supply conduit having two branches connected with the furnace air chambers, two branches connecting said chimney conduit with the air supply conduit branches, further valves for individually closing the air supply conduit branches, and other valves arranged for individually closing the chimney conduit branches at points between the connections of the chimney conduit branches with the chimney conduit and with said air supply conduit branches.
- 50 10. In apparatus for reversing the flow of heating gas and air in an alternately heated regenerative furnace having air chambers and gas chambers; a gas supply conduit having two branches, a valve for directing gas from said supply conduit into either of said branches, a chimney conduit connected between each furnace gas chamber and the related branch, other valves for closing off said branches individually, valves for individually closing the chimney conduits at points between the chimney and the branches of the gas conduit, an air supply conduit, a further valve for closing said air supply conduit, said air supply conduit having two branches connected with the furnace air chambers, two branches connecting said chimney conduit with the air supply conduit branches, further valves for individually closing the air supply conduit branches, and other valves arranged for individually closing the chimney conduit branches at points between the connections of the chimney conduit branches with the chimney conduit and with said air supply conduit branches.
